UNITED STATES PATENT OFFICE.

OLLIE C. GEORGE, OF CRYSTAL LAKE, ILLINOIS.

DESIGN FOR A GARDEN SEAT.

Application filed January 29, 1925. Serial No. 12,190. Term of patent 7 years.

To all whom it may concern:

Be it known that I, OLLIE C. GEORGE, a citizen of the United States, residing at Crystal Lake, in the county of McHenry and State of Illinois, have invented a new, original, and ornamental Design for a Garden Seat, of which the following is a specification, reference being had to the accompanying drawing, forming part thereof.

The figure is a perspective view of a garden seat showing my new design. This garden seat constitutes an independent and complete article of garden furniture and is manufactured and sold as such.

I claim:—

The ornamental design for a garden seat, as shown.

OLLIE C. GEORGE.
